C. D. PETTIS.

BRAKE SHOE.

APPLICATION FILED JULY 21, 1913.

1,100,094.

Patented June 16, 1914.

UNITED STATES PATENT OFFICE.

CLIFTON D. PETTIS, OF RIDGEWOOD, NEW JERSEY.

BRAKE-SHOE.

1,100,094.

Specification of Letters Patent. Patented June 16, 1914.

Application filed July 21, 1913. Serial No. 780,314.

To all whom it may concern:

Be it known that I, CLIFTON D. PETTIS, a citizen of the United States, and a resident of Ridgewood, county of Bergen, State 5 of New Jersey, have invented certain new and useful Improvements in Brake-Shoes, of which I do declare the following to be a full, clear, and exact description.

This invention has relation to that class 10 of brake shoes in which ductile metal parts are employed for reinforcing or strengthening the shoe. An example of this type of brake shoe is illustrated in United States Letters Patent No. 1,065,716, granted to me 15 June 24, 1913.

The invention consists in the features of novelty hereinafter described, illustrated in the accompanying drawing and more particularly pointed out in the appended claims.

20 Figure 1 is a view in side elevation of a brake shoe embodying my invention. Fig. 2 is a plan view. Fig. 3 is a view in central longitudinal section on line 3—3 of Fig. 2, the body of the brake shoe being omitted. 25 Fig. 4 is an inverted plan view of the pan-shaped back or shell of the shoe. Fig. 5 is a view in cross-section on line 5—5 of Fig. 2. Fig. 6 is a view in cross-section on line 6—6 of Fig. 2.

30 In the drawings, 10 designates the body of a brake shoe preferably formed of cast metal, although other suitable material may be used for such purpose.

At the back of the body 10 of the brake 35 shoe and connected thereto in the casting operation (if cast metal be employed) is the pan shaped shell or back 11 preferably formed from a thin plate of ductile metal. Adjacent the ends of the pan shaped back 40 or shell 11 are formed the holes 12 and 13, and adjacent the center of the back or shell 11 are formed the holes 14.

Within the pan shaped back or shell 11 are placed the supplemental reinforcing rods 45 or bars that are preferably formed from round wire bent in manner hereinafter described. In the preferred form of my invention, I employ two sets of rods or wires 15 and 16 that overlap each other at the 50 central portion of the shoe. The wires 15 have formed integrally with their inner ends, the upstanding U-shaped loop 17, while the wires 16 have formed integrally with their inner ends, the upstanding U-shaped 55 loop 18. The free ends of the wires 15 have

formed integral therewith, the upstanding portions 19 (see Figs. 1 and 5), the laterally turned portions 20, the inwardly turned portions 21, the downwardly bent portions 22 and the inwardly bent ends 23. Similarly, the free ends of the rods or wires 16 have the outwardly bent portions 19^a, the laterally turned portions 20^a, the inwardly turned portions 21^a, the downwardly turned portions 22^a and the inwardly bent ends 23^a. 60 65

In connecting the rods or wires 15 and 16 to the back or shell 11, these wires will be first formed as straight, U-shaped links and their free ends will first be passed through the central holes 14 of the back or 70 shell 11, after which the wires 15 and 16 will be bent at substantially right angles to the U-shaped loops 17 and 18 and will be extended along the inner face of the pan or shell 11. The free ends of the wires 75 15 and 16 will then be passed outward through the holes 12 adjacent the ends of the pan or shell 11, after which the wires will be bent, as shown in Figs. 1 and 2, the free ends of the wires being passed 80 downwardly through the holes 13 of the pan or shell 11, and the free ends of the wires will be bent inwardly, as indicated by dotted lines in Fig. 2, and as shown by full lines in Figs. 3 and 5. When the parts are 85 thus assembled, the wires 15 and 16 will be securely interlocked with the back or shell 11 and the end and center portions of the wires will form, respectively, the end and center lugs of the shoe. With the parts thus 90 95 assembled, the pan or shell will be placed within the mold and the cast metal to form the body of the shoe will be poured and will securely interlock with the pan or shell and with the wires.

My present invention affords an extremely simple and effective construction of reinforced brake shoe and, inasmuch as the center and end lugs are integral with the reinforcing bars or wires 15 and 16, all 100 danger of the separation of the body of the shoe from the lugs is effectively guarded against.

It is obvious that the precise details of construction above set out may be varied 105 without departing from the spirit of the invention and that features of the invention may be employed without its adoption as an entirety.

Having thus described my invention, what 110

I claim as new and desire to secure by Letters Patent, is:—

1. A brake shoe comprising a cast metal body and two sets of reinforcing rods with 5 in said body, each set of rods extending from adjacent one end of the shoe to a point beyond the center thereof and having an upturned U-shaped bend, the central portion of both members of one set of rods being 10 located within the central portion of the other set of rods.
2. A brake shoe comprising a body and reinforcing rods extending lengthwise of said body, said rods having their outer ends 15 formed with L-shaped angular bends extending above the back of the shoe and forming both the longitudinal and transverse portions of the end attaching lugs.
3. A brake shoe comprising a body and 20 reinforcing rods extending lengthwise of said body to points adjacent the ends of the shoe, the end portions of said rods being bent upwardly above the back of the shoe and transversely of the shoe at each side of 25 the longitudinal center thereof to form lugs for arresting the end thrust of the brake head.
4. A brake shoe comprising a body and reinforcing rods extending lengthwise of 30 said body to points adjacent the corners thereof, said rods having portions bent upward above the face of the shoe adjacent said corners and inwardly transversely of the shoe to form lugs for receiving the end 35 thrust of the brake head.
5. A brake shoe comprising a body, a ductile metal back having holes therein and reinforcing rods extending lengthwise of the body inside of said back, said rods being 40 substantially the size of said holes and passing outwardly therethrough beyond said back.
6. A brake shoe comprising a body, a 45 perforated ductile metal back, rods extending lengthwise inside of said back, said

rods passing outwardly through the perforated back and bent to form an attaching lug for the shoe.

7. A brake shoe comprising a body provided with a ductile metal back having 50 holes adjacent its ends and adjacent its center, and rods located within said back, portions of said rods extending through the holes of the back to form attaching lugs.

8. A brake shoe comprising a body provided with a ductile metal back having holes 55 adjacent its center and ends and rods located within said back, the central portions of said rods extending through the central holes of the back to form a center lug, and 60 the ends of said rods passing through the end holes of said back and bent to form end lugs.

9. A brake shoe comprising a body provided with a ductile metal back having holes 65 therein adjacent its center and ends, rods located within said back, the central portions of said rods extending through the central holes of the back and bent to form a central lug, and the end portions of said 70 rods passing through said back and provided with L-shaped angular bends to form the end lugs of the shoe.

10. A brake shoe comprising a body provided with a ductile metal back having holes 75 therein adjacent its center and ends, rods located within said back, the central portions of said rods extending through the central holes of the back and bent to form a center lug, the end portions of said rods 80 passing through said back and provided with L-shaped angular bends to form the end lugs of the shoe, and the extreme ends of said rods being passed through the back and bent inside thereof to interlock with 85 the back.

CLIFTON D. PETTIS.
